UNITED STATES PATENT OFFICE.

GEORGE J. CRAMER, OF CHAMOIS, MISSOURI.

MAIL-CRANE.

No. 835,404.

Specification of Letters Patent.

Patented Nov. 6, 1906.

Application filed February 13, 1906. Serial No. 300,887.

To all whom it may concern:

Be it known that I, GEORGE J. CRAMER, a citizen of the United States of America, residing at Chamois, in the county of Osage and 5 State of Missouri, have invented new and useful Improvements in Mail-Cranes, of which the following is a specification.

This invention relates to improvements in mail-cranes for supporting mail-bags in position to be caught by the catcher-hook on the mail-car of a moving train, the object of the invention being to provide a simple construction of crane which is adapted to operate in such manner as to sustain the bag to permit 15 it to be caught by the catcher-hook of a train moving in either direction along the track.

A further object of the invention is to provide a mail-crane having a swinging bag-supporting frame adapted to swing in either 20 direction and to normally remain out of operative position, so that it will not constitute a source of danger to the passengers of moving trains or brakemen hanging on the ladders of freight trains.

25 In the accompanying drawings, Figure 1 is a side elevation of a mail-crane embodying my invention, showing the swinging frame arranged in operative position to support a mail-bag and indicating in dotted lines the 30 catcher mechanism of a mail-car. Fig. 2 is a top plan view of the crane with the bag removed, but still showing the swinging crane in operative position. Fig. 3 is a horizontal section through the top of the post on the 35 line of the sliding pivot-bolt, showing the swinging frame in normal position.

Referring now more particularly to the drawings, the crane comprises a supporting-post 1, which may be fixed at its lower end to 40 a suitable base or embedded in the ground and may be sustained at each side by a bracing rod or iron 2. The upper end of the post carries a swinging bag-supporting frame 3, comprising a vertical body portion 4, having 45 outwardly-extending upper and lower suspending-arms 5 and 6.

The body portion 4 passes through and is journaled to swing in a horizontal plane in the eye members of eyebolts 7 and 8, extending 50 horizontally through the post, the lower bolt 7 being provided with a securing-nut 9. The lower end of the body portion 4 of the swinging frame is provided with a bearing-surface 10 to engage the bolt 7, whereby the 55 frame is held from downward movement.

The upper eye-bolt 8 is slidably mounted in the post and in brackets or wear-plates 11 and 12, fixed to the front and rear faces thereof, and said bolt is provided at its rear end with a nut or head 13, against which 60 bears a coiled spring 14, encompassing the stem of the bolt between said head or nut and the rear bracket or wear-plate 12. The bracket 12 carries a rearwardly-projecting hood or shield 15, which extends over the 65 rearwardly-projecting portion of the hood and the spring to protect the same from rain and snow; but any other suitable form of protector may be employed. A bracket 16 is also fixed to the front wear-plate 11 and 70 carries a forwardly-projecting guard or shield 17 to overlie the swinging frame and bag when the frame is in supporting position and prevent snow and rain from falling directly from above thereon.

75 On the body portion 4 of the swinging frame is a bearing pin or projection 18, adapted to engage the face of the bracket 11. This pin or projection is so arranged as to force the upper end of the swinging frame 80 away from the post when it comes in contact with the bracket 11 and to thereby draw upon and slide the pivot-bolt 8 forward against the resistance of the spring 14, whereby the pressure of the spring and the 85 frictional engagement of the pin 18 with the bracket 11 will hold the frame 3 in supporting position or extending directly outward from the front face of the post, as shown in Figs. 1 and 2. The swinging frame in such position is adapted to hold the mail-bag in operative relation to the catcher-hook of a passing mail-car, as will be readily understood, and it will be apparent that the force of engagement of the catcher-hook with the bag 90 will swing the frame free on its pivot in the direction of movement of the passing train, and thereby slide the pin 18 out of engagement with the bracket-plate 11, allowing the spring 14 to expand and hold the swinging 95 frame at right angles to its normal position.

To reset the frame, it is swung by the operator to the supporting position (shown in Figs. 1 and 2) against the resistance of the spring, the arrangement of the pivotal connections 100 allowing the frame to swing in either direction in an obvious manner, so that a bag may be supported therefrom to be caught by a train moving in either direction.

The bag 19 may be of any preferred con- 110

struction and is provided with end straps or loops 20 and 21, carrying suspending-rings 22 to engage the free ends of the arms 5 and 6, one of the straps, such as the strap 21, being 5 preferably adjustable to enable any slack resulting from the stretching of the bag to be taken up any time. Rings or loops 23, applied to the arms 5 and 6, hold the rings 22 from inward movement beyond the desired 10 point and may act as handholds to enable the operator to conveniently swing the frame.

It will be seen that the crane is simple in construction, may be manufactured and 15 erected at a comparatively low cost, and may be efficiently used along single-track railways for supporting bags to be taken up by trains passing in both directions. It will also be seen that when swung in either direction 20 by the action of the catcher-hook engaging the bag the swinging frame will quickly release the bag, whose rings 22 will slide off the free ends of the arms 5 and 6, and the frame will remain in the position to which it 25 is swung out of operative relation until again adjusted for operation by the attendant in charge.

Having thus described the invention, what is claimed as new is—

30 1. A mail-crane comprising a supporting-post, a bag-supporting frame mounted upon the post for swinging and tilting movement, means for resisting the tilting movement of the frame, and a projection upon the frame 35 adapted to engage the post to tilt the frame and hold it in supporting position against the resistance of said resisting means.

2. A mail-crane comprising a supporting-post, eyebolts mounted upon said post, one 40 of said bolts having a sliding movement, a swinging frame pivotally mounted upon said bolts, said frame being adapted to swing in either direction thereon, a spring associated with the sliding bolt to hold the swinging 45 frame in any of its adjusted positions, and a projection upon the frame to engage the post to hold the frame in operative position against the resistance of said spring.

3. In a mail-crane, a post, a swinging 50 frame mounted thereon and provided with suspending-arms, stops upon the free ends of the arms to limit the inward movement of the bag suspended therefrom, said stops forming handholds and means for holding 55 the frame in adjusted position.

4. In a mail-bag crane, the combination of 60 a supporting-post, eyebolts carried by the post, one of said eyebolts having a sliding movement, a spring for resisting forward movement of said sliding eyebolt, a swinging frame journaled upon said eyebolt and provided with suspending-arms, and a projection upon the frame to engage the face of the post and slide the movable eyebolt forward

to place the spring under tension when said 65 frame is arranged in operative position.

5. In a mail-crane, the combination of a supporting-post, brackets arranged upon the front and rear faces of the upper end of the post, eyebolts carried by the post, the upper 70 eyebolt having a sliding movement in the post and bracket and projecting rearwardly therefrom, a spring surrounding the upper bolt between a head upon the rear end thereof and the rear bracket and serving to resist 75 forward movement of said bolt, a swinging frame pivotally mounted upon the eyebolts and provided with suspending-arms, and a projection upon the frame having oppositely-extending portions to engage the front 80 bracket when the frame is moved from either of its normal positions to operative position to effect a forward sliding movement of the upper eyebolt against the resistance of the spring to hold said frame in supporting position. 85

6. A mail-crane comprising a supporting-post, a swinging bag-supporting frame journaled at top and bottom in bearings upon the post, one of said bearings having a sliding 90 movement, means for resisting such movement, and a projection upon the frame to engage the post to hold the frame in operative position against said resistance.

7. A mail-crane comprising a supporting-post, bearings upon the post, one of said bearings having a sliding movement, a bag-supporting frame journaled in said bearings, spring means for resisting movement of the sliding bearing, and a projection upon the 100 frame to engage the post to hold the frame in operative position against the resistance of said spring means. 95

8. A mail-crane comprising a supporting-post, bearings upon said post, one of said 105 bearings having a sliding movement, a spring for normally holding the sliding bearing retracted, a swinging bag-supporting frame journaled in said bearings, and a projection upon the frame, operative to engage the post 110 when the frame is in supporting position to hold the same in such position against the resistance of said spring.

9. A mail-crane comprising a supporting-post, bearings upon the post, one of said 115 bearings being movably mounted, a spring associated with said bearing to resist the outward movement thereof, a bag-supporting frame journaled in said bearings, and means upon said frame to engage the post, whereby 120 the movable bearing may be adjusted so that the pressure of its controlling-spring will hold the supporting-frame in operative position. 125

10. A mail-crane comprising a supporting-post, bearings upon the post, one of said bearings being slidably mounted, a spring resisting outward movement of said sliding bearing, a swinging bag-supporting frame jour-

naled in said bearings, a wear member upon the post, and a projection upon the frame to engage said wear-plate to force the frame and movable bearing outward, whereby the 5 spring will serve to hold the frame in operative position.

11. In a mail-crane, a post, a swinging frame mounted thereon and provided with suspending-arms, said arms being provided

with loops forming stops and handholds, and 10 means for holding the frame in adjusted position.

In testimony whereof I affix my signature in presence of two witnesses.

GEORGE J. CRAMER.
